UNITED STATES PATENT OFFICE.

AUGUST MATHIS, OF CHICAGO, ILLINOIS, ASSIGNOR TO MATHIS BROTHERS COMPANY,
A CORPORATION OF INDIANA.

AIR-HEATER.

No. 909,632.

Specification of Letters Patent.

Patented Jan. 12, 1909.

Application filed November 18, 1908. Serial No. 462,753.

To all whom it may concern:

Be it known that I, AUGUST MATHIS, a citizen of the United States of America, and a resident of Chicago, in the county of 5 Cook and State of Illinois, have invented certain new and useful Improvements in Air-Heaters, of which the following is a specification.

This invention relates to that class of air heaters in which the air to be heated is brought into contact with a series of coils through which steam as the heating medium passes, preferably the exhaust steam from the engine employed in the air heating system. And the present invention has for its object to provide a simple and efficient structural arrangement and combination of parts whereby a very efficient and economical heating effect is attained, and which at the same time increases the efficiency of the engine, to the exhaust end of which it is connected, all as will hereinafter more fully appear.

In the accompanying drawings: Figure 25 1, is a vertical sectional elevation on line $\alpha-\alpha$, Fig. 2. Fig. 2, is a horizontal sectional view in line $\alpha'-\alpha'$ Fig. 1. Fig. 3, is a fragmentary detail sectional elevation illustrating the means of attachment between the 30 spiral coils and the headers with which they have communication.

Similar numerals of reference indicate like parts in the several views.

Referring to the drawings, 1 represents 35 a portion of the trunk or casing through which the air to be heated is passed in manner usual to air heating systems.

2 is the tubular supply head of the present heater arranged at one side of the casing 1 40 and connected to the exhaust end of an engine, or other suitable source of steam supply. 3 is a counterpart tubular steam and water discharge head arranged in parallel and separated relation to the supply head 2 45 aforesaid, and connected to a suitable receiver for the water of condensation which forms continually in the practical operation of the system.

4, are a series of upper tubular manifold 50 heads extending laterally from the steam supply head 2; such manifold heads have a parallel and separated relation to each other and arranged within the casing 1 to approximately cover the cross area of the 55 same as shown in Fig. 2.

5, are a corresponding series of lower tubular manifold heads extending laterally from the discharge head 3, and having an arrangement in the casing 1 similar to the heads 4 above described. Such lower manifold heads 5 are of a much smaller diameter than the upper manifold heads 4, so as to offer less impedance to the passage of the air to be heated, and at the same time admit of the free discharge of the water of condensation coming from the air heating coils, now to be described.

6, are spiral coils of pipe, a series of which are individual to an individual upper and lower manifold head 4 and 5, and are connected thereto preferably by the special means hereinafter described, and have a separated relation to each other and to the next adjacent coils of the adjoining series, as shown in Fig. 2.

7, are a series of connecting nipples by which the respective ends of the spiral coils 6 are connected to the manifold heads 4 and 5 aforesaid. In their preferred form each nipple will have an externally screw-threaded shank 8 adapted to screw into the wall of a manifold head, and an internally screw-threaded neck 9 adapted to screw on to the ends of a spiral coil, as shown in Figs. 1 and 3.

Having thus fully described my said invention what I claim as new and desire to secure by Letters Patent, is:

1. In an air heater or the like, the combination of counterpart tubular supply and discharge heads arranged in separated relation, series of manifold heads extending laterally from the supply and discharge heads and arranged in separated relation, a series of spirally coiled pipes arranged between pairs of said manifold heads and communicating therewith, and a casing inclosing said manifold heads and coiled pipes, substantially as set forth.

2. In an air heater or the like, the combination of upper and lower tubular supply and discharge heads arranged in separated relation, series of manifold heads extending laterally from said supply and discharge heads and arranged in separated relation, a vertical series of spirally coiled pipes arranged between pairs of said manifold heads and communicating therewith, and a casing inclosing said manifold heads and coiled pipes, substantially as set forth.

3. In an air heater or the like, the combination of counterpart tubular supply and discharge heads arranged in separated relation, series of manifold heads extending laterally from the supply and discharge heads and arranged in separated relation, one series of manifold heads having a smaller diameter than the other series of manifold heads, a series of spirally coiled pipes arranged between pairs of said manifold heads and communicating therewith, and a casing inclosing said manifold heads and coiled pipes, substantially as set forth.

4. In an air heater or the like, the combination of upper and lower tubular supply and discharge heads arranged in separated relation, series of manifold heads extending laterally from said supply and discharge heads and arranged in separated relation, the lower series of manifold heads having a smaller diameter than the upper series of manifold heads, a vertical series of spirally coiled pipes arranged between pairs of said manifold heads and communicating therewith, and a casing inclosing said manifold heads and coiled pipes, substantially as set forth.

5. In an air heater or the like, the combination of counterpart tubular supply and discharge heads arranged in separated relation, series of manifold heads extending laterally from the supply and discharge heads

and arranged in separated relation, a series of spirally coiled pipes arranged between pairs of said manifold heads, a series of 35 tubular nipples connecting the ends of said coiled pipes to the manifold heads, each nipple having an externally screw-threaded shank and an internally screw-threaded neck, and a casing inclosing said manifold 40 heads and coiled pipes, substantially as set forth.

6. In an air heater or the like, the combination of upper and lower tubular supply and discharge heads arranged in separated relation, series of manifold heads extending laterally from said supply and discharge heads and arranged in separated relation, a vertical series of spirally coiled pipes arranged between pairs of said manifold 50 heads, a series of tubular nipples connecting the ends of said coiled pipes to the manifold heads, each nipple having an externally screw-threaded shank and an internally screw-threaded neck, and a casing inclosing 55 said manifold heads and coiled pipes, substantially as set forth.

Signed at Chicago, Illinois, this 12th day of November, 1908.

AUGUST MATHIS.
